US0D1071933S

(12) **United States Design Patent** (10) **Patent No.:** **US D1,071,933 S**
(45) **Date of Patent:** **** Apr. 22, 2025**

(54) **MONITOR HOUSING**

(71) Applicant: **Michael Bihlmeier**, Peoria, AZ (US)

(72) Inventor: **Michael Bihlmeier**, Peoria, AZ (US)

(**) Term: **15 Years**

(21) Appl. No.: **29/946,070**

(22) Filed: **Jun. 6, 2024**

(Continued)

FIG. 1 is a top front perspective view of a monitor housing shown in accordance with my new design;

FIG. 2 is a bottom front bottom perspective view of the monitor housing shown in FIG. 1;

FIG. 3 is a front elevation view of the monitor housing shown in FIG. 1;

FIG. 4 is a rear elevation view of the monitor housing shown in FIG. 1;

FIG. 5 is a left side elevation view of the monitor housing shown in FIG. 1;

FIG. 6 is a right side elevation view of the monitor housing shown in FIG. 1;

FIG. 7 is a top plan view of the monitor housing shown in FIG. 1; and,

FIG. 8 is a bottom plan view of the monitor housing shown in FIG. 1.

1 Claim, 8 Drawing Sheets
